(57) **CLAIM**

The ornamental design for a nut ring for fishing rod reel seat as shown and described herein.

DESCRIPTION

FIG. 1 is a perspective view from a left side of a nut ring for fishing rod reel seat showing the new design;

FIG. 2 is a front view of the nut ring for fishing rod reel seat of FIG. 1 showing the new design;

FIG. 3 is a rear view of the nut ring for fishing rod reel seat of FIG. 1 showing the new design;

FIG. 4 is a top plan view of the nut ring for fishing rod reel seat of FIG. 1 showing the new design;

FIG. 5 is a bottom plan view of the nut ring for fishing rod reel seat of FIG. 1 showing the new design;

FIG. 6 is a right side view of the nut ring for fishing rod reel seat of FIG. 1 showing the new design;

FIG. 7 is a left side view of the nut ring for fishing rod reel seat of FIG. 1 showing the new design;

FIG. 8 is a cross-sectional view of the nut ring for fishing rod reel seat of FIG. 2 showing the new design;

FIG. 9 is a cross-sectional view of the nut ring for fishing rod reel seat of FIG. 7 showing the new design; and,

FIG. 10 is a reference view showing a state of the nut ring for fishing rod reel seat of FIG. 1 in use.

The broken line showing of portions of the fishing rod reel seat are included for illustration only and form no part of the claimed design.
